UNITED STATES PATENT OFFICE.

MICHAEL PEMBROKE, OF MONTPELIER, VERMONT.

STONE-POLISHING WHEEL.

No. 900,947.

Specification of Letters Patent. Patented Oct. 13, 1908.

Application filed April 25, 1908. Serial No. 429,117.

To all whom it may concern:

Be it known that I, MICHAEL PEMBROKE, a citizen of the United States, residing at Montpelier, county of Washington, State of Vermont, have invented certain new and useful Improvements in Stone-Polishing Wheels, of which the following is a specification.

This invention relates to polishing wheels and particularly to a wheel for polishing granite or similar stone. In wheels of this sort it has been customary to use a plate provided with flanges of various shapes and forms which work upon the polishing material and reduce the surface of the stone to the proper condition, and of the many forms of flanges employed those of scroll shape have been found to be of great advantage, inasmuch as they tend to gradually drag towards the center of the wheel the polishing material. The usual polishing material is made up of hard chilled iron pellets or shot mixed with sand and wet with water.

One of the great difficulties in the successful operation of a scroll flange wheel is the liability of the shot to lodge under the flange and cause it to run, giving it a ball bearing action during which the polishing effect is entirely lost for that portion of the wheel at least. Inasmuch as it is found of great advantage to use a uniform spiral flange which will evenly feed the polishing material towards the center of the wheel, I have devised my present invention which, while retaining the old scroll feature, is so constructed and arranged in its various parts as to afford all of the advantages of a continuous scroll and yet obviate the difficulties incident upon the use of such a continuous scroll by forming a scroll in successive sections spaced apart in such a way as to make it impossible for the running of the wheel on the shot to occur. This affords a uniform abrasion of the surface and successfully prevents any tendency to dig or gouge the surface at any particular part, and further, makes it possible to work up close to the edge of the bed or in the corners where the crowding of the mud would make the wheel most liable to run.

In the accompanying specification, in which my invention is more fully described, I have set forth as illustrative thereof, an embodiment which is illustrated in the drawings forming a part of the specification and

to which reference is made by numerals used to indicate corresponding parts throughout.

In the drawings, Figure 1 is a bottom view of my polishing wheel, and Fig. 2 is a side view of the same.

1 is a disk which forms the frame or body of the wheel having a central hole 2 which affords an escape for the mud as it works radially towards the center of the wheel.

3 are lugs to receive the driving shaft.

4 are detachable spiral flanges attached to the plate 1 by set screws 5. The flanges 4 are provided with the usual sharpened runner shaped forward ends 4¹ and are arranged successively to form gradually increasing spirals from the center outward to the edge of the disk 1. I preferably provide a double set of flanges 4.

Between the rear end 4² of each flange section 4 and the forward sharpened or runner shaped end 4¹ of the section next following is left a space 6 which forms breaks in the otherwise uniform spiral. These breaks are arranged in such a manner that they are covered on each side by the flanges next within and without them and they are preferably arranged just behind the advanced end of the flange next outside. In other words, the forward end of each scroll slightly overlaps the rear end of a scroll just within it. In this way when a shot which has begun to run spirally beneath a flange, is dropped into a space 6 it is met by a mass of mud which has just been hooked in by the forward end of the flange next outside of it and which has just begun to move inward under the influence of the flange. In this way the shot is deflected and prevented from running under the forward end of the flange section which tracks the section which it has just left. For this reason it is possible to use a succession of flanges which give all the advantages of the continuous uniform spiral and yet avoid the danger of the continued running of shot under the flange face.

Various modifications may obviously be made in the number of flanges used in the construction of the spiral and even variations are possible in the relative arrangement of the spiral sections and the spaces therebetween, all without departing from the spirit of my invention.

What I therefore claim and desire to secure by Letters Patent is:

1. A polishing wheel comprising a plate, a

5 plurality of successively arranged flanges spirally disposed around its center, each of said flanges tracking the flange next in advance of it but being spaced apart therefrom the spaces being continuous.

10 2. A polishing wheel comprising a plate, a plurality of spiral flanges disposed around a center each of said flanges tracking the flange next in advance of it and each of said flanges having a sharpened forward end the spaces between said flanges forming a continuous channel.

15 3. A polishing wheel comprising a plate, a plurality of spiral flanges disposed around a center and comprising successive flange sections each of said sections tracking the sec-

tion next in advance of it the spaces between the convolutions of said spiral being continuous.

4. A polishing wheel comprising a plate, a 20 plurality of successively arranged flanges spirally disposed about its center each of said flange sections having its forward end slightly overlapping the rear of the section next within it the spaces between said spirally disposed flanges being continuous.

25 In testimony whereof I affix my signature in presence of two witnesses.

MICHAEL PEMBROKE.
